UNITED STATES PATENT OFFICE

155,114

DESIGN FOR A FRUIT PACK

Philip M. Williams, Oakland, Maine

Application November 3, 1947, Serial No. 142,279

Term of patent 14 years

(Cl. D58—13)

To all whom it may concern:

Be it known that I, Philip M. Williams, a citizen of the United States, residing at Oakland, in the county of Kennebec, State of Maine, have invented a new, original, and ornamental Design for a Fruit Pack, of which the following is a specification, reference being had to the accompanying drawing, forming part thereof.

Fig. 1 is a top plan view of a fruit pack, showing by new design,

Fig. 2 is an edge view thereof, and,

Fig. 3 is a section on the line 3—3 of Fig. 1.

I claim:

The ornamental design for a fruit pack, as shown.

PHILIP M. WILLIAMS.
